CATSUP BOTTLE DRAINING RACK OR THE LIKE

William G. Indrunas, 251 E. 32nd St.,
New York, N.Y. 10016

Filed Feb. 25, 1970, Ser. No. 21,618

Term of patent 14 years

Int. Cl. D7—99

U.S. Cl. D44—29

FIG. 1 is a top plan view of a catsup bottle draining rack or the like, showing my new design;

FIG. 2 is a side elevational view thereof;

FIG. 3 is a bottom plan view thereof;

FIG. 4 is a front elevational view thereof; and

FIG. 5 is a rear elevational view thereof.

I claim:

The ornamental design for a catsup bottle draining rack or the like, substantially as shown.
